METHOD OF FORMING A FOUNDATION
STRUCTURE FOR BRIDGES, PIERS, DOCKS,
SEA WALLS, AND THE LIKE

Vincent Schiavi, Wilmington, Del.

Application March 31, 1938, Serial No. 199,222

1 Claim. (Cl. 61—50)

The present invention relates to a foundation structure for bridges, piers, docks, sea walls and the like, and more particularly to a new, novel and improved method for constructing semi-monolithic foundations for use with the above mentioned constructions.

One of the objects of the invention is to provide a method of forming a foundation construction consisting of preformed slabs of concrete or other suitable material having depending aprons or side walls, which slabs are adapted to be placed upon bearing pilings provided with a cap placed or poured thereon.

Still another aim of the invention is the formation of a semi-monolithic construction for use with foundations, which may be piling, caissons or concrete poured on bed rock, which construction will have an appearance and which will be equal in strength to a monolithic structure.

Other aims and objects will be apparent from the detailed description hereinafter appearing, when taken in conjunction with the appended drawings forming a part hereof, to which reference is now made and in which:

Fig. 1 is a vertical sectional view showing a foundation consisting of piling, upon which a concrete base has been placed or poured thereon, and showing the preformed slabs in place.

Fig. 2 is a side elevational view, partly broken away, of the construction of Fig. 1.

Fig. 3 is a sectional view taken on line 3—3 of Fig. 2.

Fig. 4 is a detail view showing how the preformed slabs are secured or locked to one another.

Fig. 5 is a sectional view of a modified form of the invention employing a bulkhead construction.

Fig. 6 is an elevational view, partly broken away, and partly in section of the form of invention shown in Fig. 5.

Fig. 7 is a sectional view taken on line 7—7 of Fig. 6.

Fig. 8 is a sectional view of still another modified form of the invention especially adapted for use in beach protection.

Fig. 9 is a sectional view of yet a further modified form of the invention.

Referring first to Figs. 1 and 2, the reference character S designates solid ground into which have been driven piling P. The piling is driven down into the ground S to the point of refusal of the piling. As shown, the piling P may be reinforced with metallic U-shaped braces B and with angle irons A. The low water level is designated by reference character W. It will be understood that the piling P forming the foundation may be

replaced by a caisson, or if desired, concrete may be poured on bed rock if the conditions are favorable for this type of construction. In other words, the foundation may take various forms, depending upon conditions, and does not constitute any material part of this invention.

The piling P, or other foundation construction, is provided with an upper wooden deck 10 or the like, upon which a base 11 is either cast in place or poured thereon. As will be seen by an inspection of Figs. 1 and 2, the base 11 is provided with spaced openings 12 therein, substantially centrally thereof. Supported upon the base 11 are precast slabs 13 of concrete or other material. It will be noted that these slabs when operatively positioned have a shape substantially resembling an inverted U. The horizontal portions 14 of the inverted U-shaped slabs rest on the upper surface of the base 11, while the vertical portions 15 of the inverted U-shaped slabs constitute aprons 16 passing beneath the surface of the water W and into the ground S. The aprons 15 of the slabs 13 shield both sides of the piling P covering the same. As will be apparent by an inspection of Figs. 3 and 4, the slabs 13 are united to each other by means of interlocking slots and protuberances 16 on the front and rear faces thereof. The horizontal portions 14 of the slabs 13 have openings 14a substantially in alignment with the openings 12 in the base 11. After the precast slabs have been positioned upon the base 11, a superstructure 17 of concrete or the like may be built, said superstructure having a downwardly projecting portion 18 formed by filling the openings 12 in the base 11 and the openings 14a formed in the horizontal portions 14 of the precast slabs 13. The superstructure 17, the horizontal portions 14 of the slabs 13, and the base 11 may be provided with reinforcing elements 19 which may take various shapes and forms and, as these form no material part of the invention, no further description thereof is deemed necessary. As an alternative method of construction, before the superstructure 17 is built, the water W may be pumped out intermediate the opposed aprons 15 of the slabs 13 surrounding the piling P and concrete poured through the openings 12 in the base 11 to completely cover the piling P and fill up the space formed by the aprons. As will be understood this will form a solid foundation.

From the above description it will be apparent that the aprons or side walls 15 add considerably to the strength of the foundation, and it will also be appreciated that the cost of construction is materially reduced. The precast slabs 13 may be

constructed while the piling P is being placed. Also, if desired, the superstructure 17 may in a large part be precast, also saving considerable time. Furthermore, the use of cofferdams is eliminated and no allowance need be made for the existing location, because of water or below water hazards or land, or below land surface hazards. The aprons of the precast slabs can be constructed so as to be used in strengthening or dressing up existing structures.

It will also be appreciated that considerable costs for insurance are obviated; costs of bracing in cofferdams eliminated; as well as the high costs which usually accompany methods of construction where men are compelled to work in cramped quarters, such as between cofferdams, bracings therein and the like. Then again the possibilities of injuries to workmen are lessened and also the dangers attending cramped working quarters and possible collapse of cofferdams.

Finally, due to the fact that the slabs 13 are precast, facings of any suitable material can be incorporated on the outer surface of the aprons 15 , which surfaces may be formed of metal, 25 marble, granite, in whole or in part. Mottled effects may be produced with various colored stones or ordinary quarried stone can be matched before placement. Also in some instances no superstructure is desirable and the horizontal portion 30 14 of the slabs 13 can be finished in any suitable manner to give the desired appearance and strength. The invention, in addition, lends itself to a cessation of construction at any point or time of day without injury or loss or damage to 35 the work already in place, which characteristic is lacking in large part with present day constructions.

Referring now to Figs. 5, 6 and 7, showing a modified form of the invention, it will be noted that only one side of the piling P is covered with a depending apron 15^a of the inverted L-shaped precast slab 13^a . The other side of the piling P is not covered, the precast slab 13^a having no depending apron on that side. The construction just described is of particular value in bulkheads 45 and beach protection.

In the modified form of the invention shown in Fig. 8 the apron 24 of one of the precast slabs 13 extends at an angle to the upper surface of the horizontal portion 14 and deep into the ground S . It will also be noted that in this arrangement 5 no superstructure 17 is provided. This constructional form is valuable in beach protection.

Fig. 9 is the modified form of the invention disclosed in Fig. 5, but showing the use of metal sheeting 50 projecting downwardly from the 10 outer edge of base 11 . This sheeting is optional and is to be used only when required to prevent erosion of existing sub soil or back filled material. It is further understood that wood or steel sheeting 50 may be used on any form of the invention, 15 if desired, in order to prevent soil erosion.

In summation, it will be apparent that while a major part of the completed sub-structure is below water, all the necessary labor to construct same is performed above water.

From the foregoing description, it will be seen that there has been disclosed a sub-structure for bridges, piers, docks, sea walls and the like, well adapted for their intended functions, as will be obvious to those skilled in the art. Various other 25 changes and modifications may be made to embody the spirit and purpose of the invention, and it is contemplated to cover such variations and to be limited in this respect only as may be necessary by the scope of the appended claim.

What I claim is:

The method of forming a foundation structure for bridges, piers, docks, sea walls and the like which comprises driving piling having an upper deck into a bed of water, casting an apertured 35 base on said deck, placing apertured interlocked precast inverted U-shaped slabs on said base providing aprons for said piling extending into said bed of water, the apertures in said inverted U-shaped slabs and said base being aligned, and 40 casting a superstructure on said inverted U-shaped slabs and interlocking said superstructure with said base through said aligned apertures.
